INVENTOR.
MARY A. RADFORD
BY *Joseph B. Gardner*
her ATTORNEY.

UNITED STATES PATENT OFFICE.

MARY A. RADFORD, OF OAKLAND, CALIFORNIA.

APPARATUS FOR TREATMENT OF THE FEET.

Application filed November 3, 1921. Serial No. 512,452.

To all whom it may concern:

Be it known that I, MARY A. RADFORD, a citizen of United States, and a resident of Oakland, county of Alameda, State of California, have invented a new and useful Apparatus for Treatment of the Feet, of which the following is a specification.

My invention relates to an apparatus for treating foot ailments, such as corns, calluses, bunions, etc.

An object of the invention is to provide means of the character described by the use of which both light and severe cases of various foot ailments may be relieved or entirely overcome in a minimum space of time.

Another object of the invention is to provide an apparatus of the character described which is extremely simple in construction, readily kept sanitary, and applicable for use with either foot.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claim.

Referring to said drawings:

Figure 1 is a perspective view of the outer member of the apparatus.

Figure 2 is a longitudinal section of the inner and outer members of the assembled device.

Figure 3 is a bottom view of the outer member.

Very briefly expressed the method I use for treating the foot, substantially comprises in heating the foot to a degree producing excessive dilation of the sweat glands, and trapping the resultant moisture discharging from the foot during such dilation. The apparatus for effecting the above, as here shown includes a rather tightly fitting rubber stocking in which the foot is placed, a loosely fitting shoe in which the stocking-covered foot is inserted, and an electric heating element arranged in the sole of the shoe.

A detailed description follows:

The apparatus in its present form, com-

prises an inner member 2 and an outer member 3. The inner member consists of a sock or stocking 4 which is made of a non-porous flexible material such as rubber or the like, and is adapted to be slipped upon the bare foot that is to be treated. The stocking is of a size to fit the foot rather snugly and preferably extends above the ankle.

The outer member 3 of the apparatus comprises a shoe 6 preferably made of rubber, canvas, or similar material, and provided with inner and outer soles 7 and 8 respectively, which are formed of a dielectric material such as rubber. The shoe is made large enough to readily enable it to fit either foot of the person. In this manner when the foot is held in the stocking and has been inserted in the shoe, a comparatively large space will be had between the major portion of the side walls of the stocking and shoe, the advantage of which will be presently explained. Arranged between the soles 7 and 8 is an electric heating element 9 which is provided with the leads 10 that extend from the rear of the shoe and are adapted to be connected to any suitable source of electric supply.

In the use of the apparatus the foot is slipped into the rubber stocking and is then inserted therewith in the shoe, after which the latter is laced and tied in the usual manner. The heating element is then energized and the device thus commences to function. As soon as the interior of shoe becomes heated and the heat thence transmitted from the stocking to the foot, there is produced in the latter an excessive dilation or functioning of the sweat glands. The rubber stocking being non-porous, the moisture exuded through the pores of the foot is prevented from escaping, thus causing the abnormal skin to be subjected to a sweltering action. The operation of the device is continued until such time as the abnormal skin is reduced to such softness as to readily enable it to be scraped off. The time usually consumed to effect the foregoing depends to a great extent on the condition of the foot, however a half hour is generally sufficient to complete the entire operation. As hereinbefore mentioned a space is provided between the side walls of the stocking and those of the shoe. In this manner the warm air currents may effec-

tively circulate around the stocking and foot and said stocking are adapted to be thereby insure the uniform distribution of heat.

10

I claim:

5 In a device of the character described, a non-porous stocking in which the foot is adapted to be inserted, a shoe in which the

encased, and a heating element associated with said shoe.

In witness whereof, I have hereunto set my hand at Oakland, California, this 25th day of October, 1921.

MARY A. RADFORD.
